UNITED STATES PATENT OFFICE.

CHARLES C. SPENGLER, OF ROCKFORD, ILLINOIS, ASSIGNOR TO AUTOMATIC PENCIL SHARPENER COMPANY, OF CHICAGO, ILLINOIS, A CORPORATION OF NEW YORK.

PENCIL-SHARPENER.

1,283,584.

Specification of Letters Patent. Patented Nov. 5, 1918.

Application filed April 29, 1918. Serial No. 231,338.

To all whom it may concern:

Be it known that I, CHARLES C. SPENGLER, a citizen of the United States, residing at Rockford, in the county of Winnebago and 5 State of Illinois, have invented certain new and useful Improvements in Pencil-Sharpeners, of which the following is a specification.

My invention relates to pencil sharpeners 10 of the type having a revolving cutter mounted on a standard and surrounded by a receptacle to catch the shavings from the cutting operation. The invention relates particularly to means for mounting the receptacle 15 upon the standard, and has for its object to provide a simple, inexpensive, efficient and lasting construction, through means of which the receptacle may be conveniently applied to and removed from the standard, and will 20 be firmly seated without vibration while in place.

The underlying features of the invention 25 are an approximately cylindrical seat, preferably concentric with the axis of revolution of the cutter, carried by the standard in position to receive the receptacle surrounding the cutter, and an opening in the wall of the receptacle to receive said seat; the seat being slightly tapered to insure a firm 30 bearing of the receptacle thereon, and being provided with a circumferential groove or grooves in a plane or planes slightly inclined to a plane perpendicular to the axis of revolution, and adapted to receive a lug 35 carried by the receptacle so that when the receptacle is placed over the seat and given a partial revolution relatively to the seat, the inclined groove will develop a camming action and lock the parts tightly together.

40 The invention will be more fully understood by reference to the accompanying drawings, in which—

Figure 1 is a perspective view of the 45 standard with the head and cutter mounted therein;

Fig. 2 is a similar view, partly in section, of the receptacle to be mounted on the head of the standard; and

Fig. 3 is a detailed view showing by an 50 axial section the coöperation of the inclined camming groove of the head with the engaging lug of the receptacle.

1 represents the standard, which is provided with a head 2 and an elongated bearing 55 3, which receives the shaft of the cutter

4, which has an outwardly presented pencil socket 5. 6 represents the receptacle having an opening 7 in its front wall to receive the socket 5, and a relatively larger opening 8 in its rear wall 8^a to receive the head 2 60 upon the standard 1. The opening 8 has an axially elongated face 9, preferably defined by an inwardly-extending flange 9^a on the rear wall, while the head 2 has an approximately cylindrical face 10 to which the face 65 9 conforms. A slight taper in the coacting faces 9 and 10 causes the parts to come to a firm seating one upon the other so as to hold the receptacle snugly in place without vibration. The face 9 carries a lug 11, conveniently provided by deflecting a portion 70 of the flange 9^a which extends into a groove 12 in the face 10 of the head 2, and said groove is in a plane slightly inclined to a plane perpendicular to the axis of revolution, 75 so that when the lug 11 is placed in the outer end of the groove, and the receptacle is rotated relatively to the head, a camming effect is developed which forces the receptacle to a firm seating upon the head. Groove 80 12 is preferably duplicated, as suggested at 12^a, at a position approximately 90° from the position of the groove 12, so that the receptacle may be secured to the head in a substantially vertical position, even though the 85 base of the standard 1 be attached to a vertical surface.

The end wall 8^a is preferably stamped from white gage metal which develops some resiliency in its flange 9^a, and this assists in 90 conforming and firmly seating the parts one upon another in a manner to resist vibration. This resiliency also assists in firmly binding the lug 11 against the wall of the groove 12, and preventing the parts from 95 shaking loose while in use.

What I claim is:

1. In a pencil sharpener, the combination of a standard having a substantially cylindrical receptacle seat, and a receptacle having an end wall formed with an opening to receive, and a resilient flange around said opening conforming to and fitting said seat and revolvably supporting the receptacle thereon, a locking connection being provided 100 between said flange and said seat drawing the receptacle firmly upon the standard by their relative rotation.

2. In a pencil sharpener, the combination of a standard having a substantially cylind-

drical receptacle seat, and a receptacle having an end wall formed with an opening to receive and a resilient flange around said opening conforming to and fitting said seat 5 and revolvably supporting the receptacle thereon, a locking connection being provided between said flange and said seat drawing the receptacle firmly upon the standard by their relative rotation, said locking connection comprising an inclined groove in the cylindrical seat and a deflected portion on the flange in position to enter said groove.

3. In a pencil sharpener, the combination of a standard having a cylindrical seat, and

a receptacle having an opening to receive 15 said seat and formed with an inturned resilient flange fitting said seat and supporting the receptacle revolvably thereon, said cylindrical seat having an inclined groove therein and said flange having its inner edge 20 deflected to provide a lug which enters said groove and which develops axial thrust upon the flange by rotation of the receptacle upon the seat.

Signed at Chicago, in the county of Cook, 25 State of Illinois, this 24th day of April, A. D., 1918.

CHARLES C. SPENGLER.
